UNITED STATES PATENT OFFICE

CHARLES KAISER, OF GREAT NECK, NEW YORK, ASSIGNOR TO MORIMURA BROS. INC.,
OF NEW YORK, N. Y., A CORPORATION OF JAPAN

DESIGN FOR A CREAM JUG OR SIMILAR ARTICLE

Application filed November 26, 1932. Serial No. 46,161. Term of patent 7 years.

To all whom it may concern:

Be it known that I, CHARLES KAISER, a citizen of the United States, and a resident of Great Neck, county of Nassau and State of New York, have invented a new, original, and ornamental Design for a Cream Jug or Similar Article, of which the following is a specification, reference being had to the accompanying drawing forming part hereof.

In the drawing forming part of this application,

I claim:

The ornamental design for a cream jug or similar article as shown.

CHARLES KAISER.
